[57]

ABSTRACT

A vehicle for transporting bridge sections, each of which is made up of two beams to be coupled in end to end relation to form a lane of a two lane bridge. The vehicle supports the two beams of each section in side by side relation on a respective side of the vehicle with the lane forming sides vertical and facing outwardly. The beams, when transported to a place of use are moved laterally outwardly on the vehicle; are rotated about a fore and aft axis to dispose the lane forming sides upwardly; are connected to the corresponding beam of the other section; are moved longitudinally and coupled together in end to end relation; and are then removed from the vehicle and placed in working position.

14 Claims, 8 Drawing Figures

VEHICLE FOR TRANSPORTING BRIDGE SECTIONS

The present invention relates to a vehicle for transporting bridge sections which include two bridge beams, each of which forms a driving lane.

For purposes of bridging large obstacles such as rivers, cuts in terrain in a minimum of time, for which no ferrying possibilities exist, bridges have been developed, which can be quickly laid and which primarily comprise two or more bridge sections mountable on a bridge-laying vehicle. The bridge sections may be coupled to each other and may be laid by the respective vehicle as a bridge. After the bridge has served its purpose, the vehicle can from the other bank again pick up the bridge sections and can lay the same at another place where they are used. These quickly layable bridges must be able to afford the possibility of moving the same within a minimum of time to various places of employment. The heretofore known bridge-laying vehicles are, however, for economical reasons not particularly suitable for the transport of the bridge sections. In addition thereto, the vehicle is designed as a track-laying vehicle with a bridge mounted thereon so that the vehicle frequently impedes traffic and is relatively slow.

It is, therefore, an object of the present invention to provide a transporting vehicle for bridge sections, which vehicle will be able within a short time to cover greater distances and will be dimensioned as to meet traffic rules and regulations.

These and other objects and advantages of the invention will appear more clearly from the following specification, in connection with the accompanying drawings, in which:

FIG. 1 diagrammatically illustrates a side view of a transporting vehicle according to the invention with bridge beams loaded thereon.

FIG. 2 is a top view of FIG. 1.

FIG. 3 shows a section taken along the line III—III of FIG. 1.

FIG. 4 illustrates the vehicle according to FIG. 3, but with the bridge beams moved outwardly beyond the normal width of the vehicle.

FIG. 5 shows in a view similar to FIG. 3 the bridge beams coupled to the bridge sections.

FIGS. 6 and 7 illustrate in a side view the mounting of the bridge on the bridge-laying vehicle.

FIG. 8 illustrates in a diagrammatic top view the transfer of a supporting unit from the transporting vehicle onto the bridge-laying vehicle.

The vehicle according to the invention for transporting bridges which can be quickly laid and the bridge sections of which comprise two bridge beams, each forming a driving lane is characterized primarily in that the bridge beams are arranged individually on the vehicle in longitudinal direction adjacent to each other and have their driving lane sides arranged parallel to the vertical vehicle axis.

For purposes of transferring the bridge beams from the transporting vehicle to the bridge-laying vehicle, it is advantageous when the bridge beams which can be coupled to each other to form a driving lane of the bridge are arranged on the vehicle adjacent to each other.

Inasmuch as the bridge comprises two driving lanes adapted to be coupled to each other, it is necessary that

the individual bridge beams which on the vehicle are located adjacent to each other are coupled to form bridge sections. To this end, it is expedient when the bridge beams of one bridge section are provided on the

5 vehicle on the outside thereof and the bridge beams of the other bridge section are located between the latter on the vehicle. For the correct location of the bridge beams on the bridge-laying vehicle, it is advantageous when the bridge beams of one bridge section are with 10 their coupling sides located adjacent to each other while the coupling sides of the outer bridge beams point to the cab of the vehicle.

Inasmuch as for coupling the bridge beams to form bridge sections, different movements are necessary 15 which cannot be carried out on the bridge-laying vehicle, the individual bridge beams are advantageously according to a further development of the invention, so mounted on the transporting vehicle that the bridge beams respectively pertaining to one and the same driving lane are moved outwardly in opposite directions beyond the lateral ends of the transporting vehicle and in this position are pivotable by an angle of 90°. After so pivoting the bridge beams, their driving lane sides are in horizontal direction located adjacent to 20 each other and are subsequently coupled by means of a bolt connection to form bridge sections.

For the special mounting of the bridge beams, a plurality of transverse spars are connected to the vehicle frame. The transverse spars are distributed over the 30 length of the vehicle frame while at least two transverse spars, especially those within the region of the front and rear ends of the bridge beams are extensible beyond the lateral ends of the vehicle. To this end, the transverse spars comprise pipes which extend beyond the width of the vehicle and in which respectively two spar sections are displaceable in opposite directions.

For securing the bridge beams during the transport thereof, and for pivoting the same, holding arms are 35 pivotally arranged at the outer ends of the spar sections. These holding arms will during the transport be directed upwardly and will engage the driving lane upper sides of the outer bridge beams. The pivoting of the holding arms is effected by hydraulic cylinder piston systems, one end of which is pivotally connected to the spar sections while the other end of said hydraulic cylinder piston systems is linked to the holding arms.

For purposes of displacing the bridge beams on the vehicle frame, within the region of the transverse spars and parallel thereto there are provided hydraulic free 40 cylinders which are adapted to be pulled out in opposite directions and are connected to the spar sections or transverse spars.

If the transporting vehicle in addition to the bridge sections also carries the supporting unit comprising 45 supports and bearing means for the bridge, it is expedient for transferring the supports and the crosshead to the bridge-laying vehicle, when the supports and the bearing means are located on the vehicle in longitudinal direction between the bridge beams pertaining to one and the same driving lane.

Finally, according to a further development of the invention, it is suggested that the supports have their foot plates located adjacent to each other and engage those bottom sides of the outer bridge beams which 50 face each other and within the region of the coupling sides of said outer bridge beams.

Referring now to the drawings in detail, for transporting a bridge 1 which can be quickly laid, there is em-

ployed as vehicle 2 a multi-axle truck with, for instance, a front axle pair 3 and a rear axle pair 4. By means of not illustrated springs, a vehicle frame 5 rests on axle pairs 3 and 4. At the front end of the vehicle frame 5 there is connected a driver's cab 6 in which there is provided the nonillustrated driving engine of the vehicle. For purposes of mounting the bridge 1 on the vehicle 2, a plurality of transverse spars 7, 8, 9 and 10 are connected behind the driver's cab 6. These transverse spars are in spaced arrangement distributed over the length of the vehicle frame 5.

The bridge 1 comprises bridge beams 11, 12, 13 and 14, which are designed as open or closed box-shaped hollow wall beams. For purposes of transporting the bridge, the bridge 1 is divided into individual parts while the bridge beams 11-14 which are used as parts of the driving track have their wide sides placed upright in longitudinal direction on the vehicle frame 5 so as to be located adjacent to each other. The driving track upper sides 15 to 18 of said bridge beams 11-14 are arranged parallel to a vertical axis of the vehicle. The total length of the two driving lanes is obtained by connecting the bridge lanes 11 and 14, and 12 and 13 to each other. To this end, the bridge beams 11-14 have equally designed coupling sides 19-22. From FIG. 2 it will be seen that the bridge beams 11, 14; 12, 13 which form one driving lane each are located adjacent to each other while their coupling sides 19, 22; 20, 21 which are to be connected to each other point in opposite directions. Connected to the bridge beams 11-14 are upwardly projecting transverse spars 23; 24, by means of which the two outwardly located bridge beams 11, 12 can be connected to each other so that both bridge beams 11, 12 form a bridge section of the bridge 1. The other bridge section is formed by the bridge beams 13, 14. The connecting means are not illustrated, but correspond to the elements 23 and 24 for beams 11 and 12. The coupling together of the partial section formed by beams 11 and 12 with the partial section formed by beams 13 and 14 is preferably effected in the manner described in my U.S. Pat. No. 3,754,293, issued Aug. 28, 1973.

For transferring the bridge from the transporting vehicle to a bridge-laying vehicle, the bridge 1 which has been divided into individual bridge beams 11-14 has to be composed to form bridge sections. The composing of the bridge beams 11-14 to form bridge sections requires a plurality of pivoting and pushing movements of the bridge beams on the transporting vehicle 2. For this reason, the transverse spars 7 and 9 have laterally extensible spar parts 25, 26 which are respectively guided in the hollow transverse spar 7 or 8. For pulling out the spar parts from the transverse spar 7 or 9 there are provided hydraulic push cylinders 27-30. The cylinders 27 and 28 are, when viewing in driving direction, located in front and behind the transverse spar 7, and the cylinders 29 and 30 are arranged in front and behind the transverse spar 9 alongside thereof. Arranged on the spar parts 25 and 26 are holding arms 31 and 32 and on the nonillustrated spar parts of the transverse spar 9 there are pivotally arranged holding arms 33 and 34 which are pivotable about a longitudinal axis of the vehicle. During the transport of the holding arms 31-34, the holding arms will engage the driving lane sides 15, 16 of the bridge beams 11, 12 (FIG. 3).

For purposes of assembling the individual bridge beams to form bridge sections, the holding arms 31-34

are by means of cylinder piston systems 35, 36 pivoted into a horizontal position. Subsequently, the bridge beams 11, 14 and 12, 13 which pertain to each other to form a driving lane are from their transporting position moved in opposite directions laterally outwardly toward the pivoted-off holding arms 31-34. This displacement is effected by means of the cylinder piston systems 27-30 which engage the spar parts 25; 26. To this end the cylinders 27-30 are disengaged from the spar parts and are fixed to the bridge beams 11, 14 and 12, 13. Subsequently, the cylinder piston systems 27-30 are with those ends which are located on the piston rod side again linked to the expandable spar parts 25; 26 which by means of said cylinder piston systems 27-30 are pulled out from both sides of the transverse spars 7 and 8 (FIG. 4). The bridge beams 11, 14 and 12, 13 are now pivoted by the holding arms 31-34 relatively toward the center of the vehicle by an angle of 90°, and in this position are by means of the spar parts 2 moved to the center of the vehicle to such an extent that the struts 23 and 24 can be connected to each other (FIG. 5). The individual bridge means 11, 12; 13, 14 are thus coupled to form bridge sections which now may be received by a bridge-laying vehicle.

The transfer of the bridge 1 from the transport vehicle 2 to a laying vehicle 37 is illustrated in FIGS. 6 and 7. The vehicle 37 has its front end provided with a laying arm 38 which is pivotable about a horizontal axis and which together with a receiving device 39 forms the laying apparatus, said receiving device 39 being arranged at the rear end of the laying vehicle 37. The vehicle 37 moves toward the rear end of the transport vehicle and threads the laying arm 38 into an inward guide of the two bridge beams 11, 12 while pulling the bridge beams 11-14 rearwardly off the vehicle frame by a portion of the length of said bridge beams 11-14. Subsequently, the laying vehicle moves its laying arm between the bridge beams 11, 12 to such an extent that the free ends can be grasped and held by the receiving device 39. The transfer of the bridge 1 from the transporting vehicle to the laying vehicle is completed and the vehicle 37 can then with the mounted bridge 1 thereon move forward to the obstacle to be crossed, and the bridge 1 may then by said vehicle 37 be laid across the obstacle.

For purposes of bridging obstacles which are wider than one length of the bridge, so-called supporting-units are employed by means of which the advanced bridge tip section rests upon the ground of the obstacle. Such supporting unit consists primarily of a support designed as a transverse yoke on which there arranged two supports with foot plates which are telescopically variable as to their length. For purposes of laying such a bridge, the entire supporting unit is mounted on the tip of the bridge and is simultaneously laid with the bridge.

According to FIGS. 1 and 2, for purposes of transporting the supporting units 40, 41, the latter are separated from the bearing or support 42 and are located on the vehicle frame 5 between the outer bridge beams 11, 12. Their foot plates 43, 44 engage the bottom sides of the outer bridge beams 11, 12 within the region of the coupling sides 19, 20. The support 42 is when viewing the vehicle in driving direction, located behind the supports between the bridge beams 13, 14. The mounting of the supporting unit between the bridge beams is so effected that following the displacement and pivoting of the bridge beams 11-14, the supporting unit is

for purposes of being received by the laying vehicle located in a correct position.

After receiving the bridge 1, the laying vehicle 37 moves from one side to the rear end of the transporting vehicle and with the tip of the bridge picks up the support 42 from the vehicle 2 (FIG. 8). After the cross-head 42 has been connected to the front end of the bridge beams 11, 12, the laying vehicle 37 turns around to such an extent that the entire device is located alongside the transporting vehicle 2. By moving forwardly and rearwardly, the laying vehicle 37 picks up the support 41, as illustrated by dot-dash lines in FIG. 8. The picking up of support 40 is effected from the other vehicle side. After changing over to the other vehicle side, the laying vehicle moves with the support 42 alongside and past the vehicle and picks up the support 40. Subsequently, the bridge 1 can be laid with the picked-up supporting unit.

It is of course, to be understood that the present invention is, by no means, limited to the specific showing in the drawings, but also comprises any modifications within the scope of the appended claims.

What is claimed is:

1. A vehicle for transporting bridge sections each comprising at least a pair of bridge beams; said vehicle including means for supporting said sections on longitudinal side by side relation with the roadway forming sides of the beams parallel to the vertical, each beam having coupling means at one end for connection to the other beam of the respective section, one beam of each section being toward the outside of the vehicle and the other beam of each section being adjacent the said one beam toward the center of the vehicle, the coupling means of said one beam of each section being at the forward end of the vehicle and the coupling means of the other beam of each section being toward the rearward end of the vehicle.

2. A vehicle according to claim 1 in which the pair of beams for making up a bridge section when coupled together are on the same lateral side of the vehicle.

3. A vehicle according to claim 1 in which one beam of each bridge section is disposed toward the outside of the vehicle and the other beams of said sections are disposed between the first mentioned beams.

4. A vehicle according to claim 1 in which the pair of beams for each section are on a respective lateral side of the vehicle and have the roadway forming surfaces vertical, said vehicle comprising means for moving each pair of beams laterally outwardly on the vehicle and for rotating the beams 90° about a fore and aft axis.

5. A vehicle according to claim 4 in which the beams of each pair have coupling means at respectively opposite ends thereof, and means for moving the beams of each pair relatively in the longitudinal direction into coupling position.

6. A vehicle according to claim 1 which includes transverse spars on the vehicle spaced in the longitudinal direction and operable for supporting engagement with said beams.

7. A vehicle according to claim 6 in which at least two spaced ones of the spars are adapted for extension laterally beyond the lateral limits of the vehicle.

8. A vehicle according to claim 1 which includes further bridge elements on the vehicle adapted for connection to said beams, said further bridge elements being disposed between said pairs of beams on the vehicle.

9. A vehicle according to claim 8 in which said further bridge elements include elements which are disposed between the outermost beams on the vehicle and engage the sides of the outermost beams which are lowermost when the said beams are in operative position.

10. A vehicle for transporting bridge sections each comprising at least a pair of bridge beams; said vehicle including means for supporting said sections in longitudinal side by side relation with the roadway forming sides of the beams parallel to the vertical, transverse

20 spars on the vehicle spaced in the longitudinal direction and operable for supporting engagement with said beams, at least two spaced ones of the spars being adapted for extension laterally beyond the lateral limits of the vehicle, said two spars being tubular, and spar elements slidably in the two tubular spars to extend the spars.

11. A vehicle according to claim 10 which includes holding arms pivotally connected to the outer ends of said spar elements, said arms being vertically disposed during transport of said sections, at least the outermost beam of each section having the roadway forming side vertical and engaging the respective said holding arms.

12. A vehicle according to claim 10 which includes fluid motors connected to said spar elements and reversibly operable for reversibly moving the spar elements in the tubular spars.

13. A vehicle according to claim 11 which includes a fluid motor connected between each holding arm and the respective spar element operable for rotating the holding arm on the spar element.

14. The method of transporting and installing two lane bridges in which a pair of beams are provided to be connected in end to end relation to form each lane of the bridge, said method including in combination the steps of placing the pairs of beams on a transport vehicle with the beams of each pair in adjacent relation and with the lane forming sides thereof vertical and facing laterally outwardly of the vehicle transporting the beams on the vehicle to a place of use, moving each

45 pair of beams laterally outwardly on the vehicle, rotating each pair of beams about a fore and aft axis to dispose the lane forming sides thereof uppermost, connecting the beams of each pair to the corresponding beams of the other pair, moving the coupled beams relatively to dispose the beams in end to end relation while at least partially supported on the vehicle, joining the coupled beams together in end to end relation, removing the resulting two lane bridge structure from the vehicle, and placing the bridge structure in position.
